DOUBLE GLAZED WINDOW SASHES

William Ross Millier, Granby, Quebec, Canada, assignor to Cresswell-Pomeroy Limited, Granby, Quebec, Canada

Filed Feb. 16, 1959, Ser. No. 793,316

5 Claims. (Cl. 20—53)

This invention relates to improvements in window sashes of the double glazed type and more particularly to the reinforcement and pivotal mounting of a supplementary sash frame for swinging movement in a main frame to open and closed positions.

A particular object of this invention is to provide a supplementary sash frame with corner reinforcing members receivable within the marginal edges of the frame and to which one arm of a hinge of a novel type is secured for mounting the supplementary sash frame for swinging movement in a recess provided in a main sash frame to open and closed positions.

Another object is to provide a novel type of hinge construction comprising a horizontally disposed hinge plate adapted to carry a sash frame and a second hinge plate pivoted at one end to one end of said first plate for pivotal movement of said plates relative to one another about a vertical axis, said second plate having a portion thereof remote from its pivotal connection disposed parallel to the pivoted axis and adapted to be secured to a second frame at right angles to the connection of said first hinge plate to said first frame so as to provide swinging movement of said first frame relative to said second frame about a vertical axis.

A particular feature of this invention resides in the provision of an inexpensive and novel hinge construction which is mountable in substantially concealed relation between a frame and a second frame so as to afford swinging movement of said first frame into and out of a recessed portion of said second frame.

The above and other objects, advantages and features characteristic of this invention will be understood more readily from the following detailed description taken in connection with the accompanying drawings, in which—

FIG. 1 is a perspective view of a corner section of a window embodying my invention.

FIG. 2 is a sectional view taken along the lines 2—2 of FIG. 1.

FIG. 3 is a plan view of a metal sheet from which a corner reinforcing member embodying my invention is formed.

FIGS. 4 and 5 are elevational views showing progressive steps in the formation of a corner reinforcing member from the sheet shown in FIG. 3.

FIG. 6 is a perspective view of a hinge embodying my invention.

FIG. 7 is a perspective view showing the corner member and the hinge in assembled relation.

FIG. 8 is a sectional view taken along the lines 8—8 of FIG. 7.

FIG. 9 is a sectional view taken along the lines 9—9 of FIG. 7 and also showing in dotted lines relative movement of the component parts of the hinge.

Referring more particularly to the drawings, 5 designates a main sash frame in which an outer glazing 6 is secured in any suitable manner in a recess 7 provided therefor. The inner side of frame 5 is provided with a recess 8 adapted to receive a supplementary sash frame 9 in which the inner glazing panel 10 is secured.

The supplementary sash frame is provided with a groove 11 along its inner edge into which the glazing panel 10 is received and a second groove 12 along its outer edge into which an L-shaped, corner reinforcing member is received. As will be seen in FIGS. 3 to 5,

2

the corner reinforcing member is formed from a T-shaped metal strip which is recessed, as indicated at 16, at the juncture of its arms 17, 18 and 19. The strip is first folded along the dotted lines 20 of arm 19 to form one channel shaped leg 21 of the corner member (see FIG. 4). Marginal portions of arms 17 and 18 are then infolded along the dotted line 22 to form the second channel shaped leg 23 of the corner member (see FIG. 5). Alternatively, the marginal portions of arms 17 and 18 may be infolded along dotted lines 22 and then arm 19 folded along dotted lines, 20.

FIG. 6 illustrates a hinge comprising a horizontal plate 25 and an L-shaped plate member including an arm 26, overlying one end of plate 25 and hinged thereto at 27 to swing about a vertical axis, and a second arm 28 disposed at right angles to said first arm 26. The leg 23 of corner reinforcing member has its web portion spot welded to the upper surface of hinge plate 25, as shown at 29 in FIG. 9. The spot welding also serves to unite the infolded marginal portions of the arms 17 and 18 which constitute the web of the channel shaped leg 23.

The hinge and corner reinforcing member is fitted to the supplementary sash frame 9 with one leg 21 of the corner member disposed within the groove 12 of the vertical rail of the sash frame 9 and the other leg 23 disposed within the groove 12 of the adjacent horizontal rail of said frame 9. The corner member is secured to the frame 9 by screws 30 which extend into the rails of frame 9 from the inner surface thereof through openings which are drilled in the assembled rails and legs 21 and 23 of the corner reinforcing member, as indicated at 31.

To mount the supplementary sash frame 9 in the main frame 5, the hinged end of hinge plate 25 and the overlying arm 26 of the second hinge plate are inserted in a horizontal recess 32 of the vertical rail of the main sash frame 5. Arm 28 of the hinge is then flatly secured by screws 33 extending through holes 34 in said arm to one side wall defining the recess 8 in the vertical rail of main sash 5, as shown in FIG. 2.

The above mounting provides for swinging of the supplementary sash frame 9 about a vertical axis but one side of the main sash 5 to allow the supplementary sash frame 9 to be swung into and out of the recess 8 in said main sash frame without interference between the marginal projection 35 of frame 9 and the underlying inner surface of main sash frame 5 at the hinged side thereof. This arrangement also affords substantially complete concealment of the hinge when the frame 9 is in the recess 8 except for small portions of the hinge members 25 and 26 about the hinge connection 27.

Although I have only shown one hinge construction at the bottom of the frames 5 and 9 it will be understood that the upper section of the frames will be similarly hinged connected by inverting the hinge so that hinge plate 25 is secured to the upper surface of the horizontal rail of supplementary sash frame 9 with the arm 28 of the other hinge plate projecting downwardly and secured along the face of recess 8 opposite the outer edge of the vertical rail of the supplementary sash frame 9. A horizontal recess similar to recess 32 is also provided in the upper section of the vertical rail of main sash frame 5 to receive the hinged end of plate 25 and arm 26 of the second hinge plate. However, due to the inverted position of this second hinge, plate 25 will overlie the arm 26 of the second hinge plate.

The embodiments of the invention in which an exclusive property or privilege is claimed are defined as follows:

1. In a window construction, a rectangular main frame, a rectangular supplementary frame receivable within said main frame, said supplementary frame being

grooved along its outer end edges, an L-shaped corner reinforcing member having its arms receivable in the grooved surfaces of adjacent sides of said supplementary frame to provide a reinforced corner therefor, means securing said corner reinforcing member in said grooves, a hinge mounting said supplementary frame in said main frame for swinging movement of said supplementary frame relative to said main frame, said hinge comprising a horizontally disposed hinge plate flatly secured to one arm of said corner reinforcing member lying in the groove of one horizontally disposed rail of said supplementary frame with a marginal portion of said hinge plate extending beyond said outer grooved edge of the adjacent vertical rail of said supplementary frame, and a second hinge plate shaped to provide an arm disposed in lapping relation to the extending marginal portion of said first plate and a second arm at right-angles to said first arm, said second arm being disposed to lie along the inner vertical edge of said main frame normally opposing the outer edge of said vertical rail of the supplementary frame, means securing said second arm to the main frame, and an axis pin connecting said first arm of the second plate to said marginal portion of said first plate for swinging movement of the first plate relative to the said first arm of the second plate about a vertical axis whereby said supplementary frame is swung into and out of its closed position with respect to said main frame.

2. A window construction as set forth in claim 1, in which said corner member securing means comprises screw members extending through one side of the supplementary frame and complementary openings provided in the corner member, said screws being embedded in said frame beyond said corner member.

3. A window construction as set forth in claim 1, in which the inner edge of said main frame is recessed at one side of the frame to receive said supplementary frame therein, said hinge plate second arm being secured along

the vertical wall defining said recess at right-angles to said side of the main frame, said main frame being further provided with a horizontal recess in the vertical wall to receive the hinged portions of said hinge plates.

- 5 4. A window construction as set forth in claim 1, in which said corner reinforcing member arms are of channel shaped configuration, the sides of each channel being receivable in the groove of the supplementary frame with the web portion disposed flush with the surface of the frame end edge.
- 10 5. A hinge for swinging connection between a main frame and a supplementary frame receivable therein, including a flat hinge securing plate having a co-planar extension and a second plate shaped to provide an arm member flatly overlying said extension of said first plate and a second arm member disposed with its broad surfaces at right angles to the plane of the first arm, said first plate extension and said first arm being pivotally connected for relative movement about an axis at right angles to said first plate and said first arm and parallel to said second arm, an L-shaped frame reinforcing member extensible along adjacent end edges of the supplementary frame, one of the arms of said reinforcing member being secured along the length of said first plate to the extension thereof and the other of the arms of said reinforcing member extending parallel to the second arm of said second hinge plate for swinging movement about the axis of said hinge relative to the second hinge plate.
